UNITED STATES PATENT OFFICE.

CARL FRIEDR. DRÖLL, OF HEIDELBERG, GERMANY.

PYROPHORIC IGNITING DEVICE FOR LAMPS OF CYCLES, AUTOMOBILES, AND THE LIKE.

961,588.

Specification of Letters Patent. Patented June 14, 1910.

Application filed June 1, 1909. Serial No. 499,297.

To all whom it may concern:

Be it known that I, CARL FRIEDRICH DRÖLL, manufacturer, a subject of the Grand Duke of Baden, and a resident of 15 Bergheimerstrasse, Heidelberg, Grand Dukedom of Baden, Germany, have invented certain new and useful Improvements in Pyrophoric Igniting Devices for Lamps of Cycles, Automobiles, and the Like, of which the following is a full, clear, and exact specification.

This invention relates to a pyrophoric igniting device for lamps of cycles, automobiles and the like. In such lamps the ignition has been connected with great difficulties, particularly in unfavorable weather in the open.

According to the present invention the ignition is effected by the production of sparks at the gas orifice, while the lamp remains closed. The sparks may be conveniently produced through the scratching of a pyrophoric mass by a sharp roughened device. The use of pyrophoric material in ordinary miners' lamps has been proposed before, but such constructions can not be used for the present purpose without further inventive effort, because the wind and the draft caused by the motion of the vehicle do not permit the few sparks produced by the device to get to the gas orifice, further because the number and direction of such sparks do not suffice for the special conditions prevailing in lamps of cycles, automobiles and the like, and finally because such known constructions are not equal to the mechanical requirements of vehicle traffic either as regards jars, easy inspection or removal. These deficiencies are overcome by the present invention by a perforation from below in the casing and reflector of the cycle or automobile lamp and the introduction through the same of a pyrophoric igniting device of suitable construction, directed toward the zone of ignition either in front or behind the gas feed pipe, so that even in a strong draft the gas is driven toward the place where the sparks are produced and the sparks are caused to pass through the escaping gases, and, if the air is still, the collection of sparks will pass directly through the upwardly passing current of gas. It is of importance in this connection that provision is made for the easy examination or removal of the igniting device. As regards the construction of the latter it is of importance that it produces

a strong collection of sparks and that the latter arrive at the ignition spot without having become diffused.

In order that this invention may be the better understood I now proceed to describe by way of example how it may be carried into effect, reference being had to the accompanying drawings and to the letters and figures marked thereon.

Figure 1 is a sectional view of an automobile lamp with a friction bolt pushed forward by a spiral spring. Fig. 2 is a sectional view showing a friction wheel adapted to be rotated against the pyrophoric body. Fig. 3 shows an arrangement, similar to Fig. 1, with longitudinally pushed friction bolt. Fig. 4 shows the arrangement of a friction bolt operated by a cam. Fig. 5 shows a further arrangement of a longitudinally pushed friction bolt, the latter being adapted to be moved out.

In the form of construction shown in Fig. 1, the lamp casing 1 is provided with a gas admission device 2 of the ordinary type. Behind the latter a tube or sleeve 3 with an inner thread is inserted. In the tube 3 is inserted the outer tube 4 of the ignition device by screws in such a manner that the friction bolt 5 is directed obliquely toward the current of gas escaping from the gas pipe 2. The ignition device 4 consists essentially of a bolt 5 subjected to spring pressure and a pyrophoric body 6 pressed against the edge of the bolt. A button 7 is pulled backward when the bolt is to be operated, and then released, when the spiral spring 8 will push it forward. The end of the friction bolt 5 is provided with rifles or is roughened, and when passing the pyrophoric body 6 produces a collection of sparks which it keeps together and carries forward by its forward movement, so that ignition is effected with certainty.

In the form of construction shown in Fig. 2 the lamp casing 9 is provided with a sleeve or tube 10 into which the ignition device is screwed which latter consists in this case of a friction knob 12 fixed to the end of a stem 11 and the oppositely situated pyrophoric body 13 which is pressed by a flat spring 14 against the friction knob 12. When turning a handle 15 of the bolt, it will be easily understood that sparks are produced from the pyrophoric body and fly directly into the path of the escaping gas.

In the form of construction shown in Fig.

3 the pyrophoric ignition device consists in a friction bolt 17 passed through the lamp casing and the reflector and a pyrophoric body 19 pressed forward by a flat spring 18. 5 In this arrangement the friction bolt 17 is operated as follows. The bolt has at its rear a pin protruding from the casing and the spiral spring 21 bearing against the collar 19* drives it forward. A collar 22 sliding 10 on the tube is provided with a flat spring 23, which engages over the pin 20 on the collar 19*; when the handle 24 of the collar 22 is retracted, the pin and friction bolt are retracted also until the flat spring 23 striking a projection 25 of the tube releases the pin 20, after which the spiral spring 21 pushes forward the friction bolt 17 with great force and directs the collection of sparks against the escaping gas.

20 In the form of construction shown in Fig. 4 the ignition device is again inserted into a special holder 26 of the lamp casing and reflector. In this case the ignition device consists of a friction bolt 28 driven forward 25 by spring pressure and a pyrophoric body 27 against which it rubs. A pin 29 of the bolt 28 extends through the casing outwardly and slides in the curved paths of a disk 31. The latter is connected to another 30 disk 32 screwed thereon so that, when the disk 32 is rotated by a handle or handles 33, the bolt 29 draws the friction bolt 28 and when passing the next step in the guiding curve 30 allows it to be pushed forward 35 again by its spiral spring, whereby, as in the previous examples the collection of sparks is thrown on the escaping gases.

In the form of construction shown in Fig. 5 a bolt 34, carrying at its end the friction 40 surface is inclosed in a sleeve 35 so that it is pressed forward by the spiral spring 36. However, its forward movement is limited by one or more cross pins 37 arranged on its rear end, such pins 37 being situated in a 45 slot of the sleeve 35, a hand wheel 38 is pushed over the rear end of the sleeve 35 and is provided with a lengthened boss which has a curved path 39, which at its side somewhat before the rise has another step or recess. The cross pin 37, which passes through the hole in the sleeve is guided in this curved path 39 and therefore draws the bolt back 50 more or less, until after passing the recess and the following rise, the bolt is again suddenly thrown forward by the spiral spring arranged behind it and produces a collection 55 of sparks. The front end of the sleeve is provided with a screw head 40 by which the igniting device can be screwed into the lamp casing and the reflector. After ignition it is 60 advisable to withdraw the bolt 34 by the partial rotation of the hand wheel 38 until its pin rests in the rear recess of the curved path 39 in which position the friction bolt 65 is removed, from the direct influences and

the heat of the burner flame and further the ignition device is quite close to its completely compressed position, so that for the repeated use only a minimum further amount of rotation of the hand wheel 38 is required. 70

It will be obvious that other forms of construction may be used than those illustrated, because the nature of the invention consists in the arrangement of an easily exchangeable pyrophoric ignition device arranged in 75 the casing and reflector of lamps of cycles, automobiles and the like, which sends a quantity of sparks directly to the zone of ignition and is operated by the pulling, rotating or pushing of an operating device 80 situated outside the lamp.

I claim:

1. A pyrophoric ignition device for the purposes described, consisting of a tube adapted to fit an opening in the lamp casing 85 and reflector, a pyrophoric piece located near the inner end of said tube, a friction-piece located in said tube and movable therein, arranged to act upon said pyrophoric piece when operated, and means for operating said friction piece from the outer end of the tube, all of said parts being carried by said tube and removable with it and occupying a transverse area less than the area of the opening in the casing or reflector, so 95 that they may be inserted or removed from the outside of said casing or reflector.

2. In a pyrophoric ignition device, the combination with the lamp casing and its reflector having an opening, a ring fitting 100 said opening, a tube fitting said ring, a pyrophoric piece carried by said tube and located near the inner end thereof, a friction-piece located in said tube and movable therein and having its outer end arranged 105 to act on the pyrophoric piece, and means also supported by said tube for operating said friction piece from the outer end of said tube said pyrophoric piece and friction piece carried by said tube occupying a 110 transverse area less than that of the ring so that said tube and the parts carried by it may be inserted and removed from the outside of the casing or reflector.

3. In a pyrophoric ignition device, the combination with the lamp casing and its reflector having an opening, an internally threaded ring fitting said opening, a tube having an externally threaded sleeve adapted to be screwed into said ring, a pyrophoric piece located near the inner end of said tube, a friction-piece located in said tube and movable therein, arranged to act upon said pyrophoric-piece when operated, and means for operating said friction-piece from the outer end of said tube, said pyrophoric-piece, friction piece and operating means being all carried by said tube and removable with it. 120

4. A pyrophoric ignition device for the 130

purposes described, consisting of a tube
adapted to fit an opening in the lamp cas-
ing and reflector, a pyrophoric piece carried
by said tube and located near the inner end
thereof, a friction piece carried by a spring-
bolt located in said tube, and means for op-
erating said spring bolt from the outer end

of said tube, said pyrophoric piece, friction
piece and operating means being all carried
by said tube and removable with it.
